UNITED STATES PATENT OFFICE.

ONAH MAUDE JACKSON, OF QUINCY, MICHIGAN.

FOLDING CHAIR.

1,184,531.

Specification of Letters Patent.

Patented May 23, 1916.

Application filed November 10, 1914. Serial No. 871,343.

To all whom it may concern:

Be it known that I, ONAH M. JACKSON, a citizen of the United States, residing at Quincy, in the county of Branch and State 5 of Michigan, have invented new and useful Improvements in Folding Chairs, of which the following is a specification.

This invention relates to folding chairs or seats, the object of the invention being to 10 provide a folding chair adapted to be applied to ordinary seat boards in circus tents or other show places, whereby a seat may be provided which will be comfortable in character and give rest and support to the back 15 of the user.

A further object of the invention is to provide a chair which may be readily applied to and removed from the seat board, which is simple of construction and capable 20 of being manufactured and sold at a low cost, which may be easily and conveniently folded for storage and transportation, and which may be provided with a carrying handle serving as a foot rest for the convenience 25 of a person in rear of the folding seat.

The invention consists of the features of construction, combination and arrangement of parts herein fully described and claimed, reference being had to the accompanying 30 drawing in which:—

Figure 1 is a perspective view showing the device applied to a seat board. Fig. 2 is a bottom plan view of the same. Fig. 3 is an end elevation showing the chair or seat 35 folded for storage or transportation. Fig. 4 is a front view of the seat as arranged for ready transportation.

My improved chair or seat comprises a seat section 1 and a back section 2.

As shown in the present instance the seat section 1 comprises a board to the forward edge of which is secured a cross strip 3 having extended ends 4, while the back section 2 comprises a board or plate cut away 45 in approximately inverted U-form so as to provide side rails 5 connected by a transverse top rail 6. The rear end of the seat section 1 fits between the lower ends of the side rails 5 and is pivotally connected there- 50 with by headed pins 7, thus adapting the seat section to fold parallel with the back section or to be disposed in an operative position at right angles thereto.

In practice, the opening in the back section 55 may be covered by an apron 8 of canvas or any other suitable material, enabling

the chair to be made much lighter than one of solid structure and a back section to be provided which will give rest and comfort to the back of the occupant of the chair. 60 The seat section may be upholstered or cushioned as desired. Links 9 connect the lower ends of the side rails of the back section with the extended ends 4 of the cross strip 3 of the seat section to brace and sustain said 65 seat section when disposed in operative position, as well as to connect the parts in a durable manner and to insure ease of folding. As shown the rear ends of the links pivotally engage headed pins or studs 10 on 70 the rails 5, and headed pins or studs 11 on the extended ends of the cross strip 3 engaging slots 12 in the links, whereby the outer end of the seat section is slidably and pivotally connected with the links to compensate for the different arcs on which the links and seat section swing. The heads of the pins 7 are so disposed that when the seat section 1 is let down for use the rear ends of the links will come in contact with said 80 heads of the pins and be reinforced and braced therefrom.

A spring clasp is provided upon the underside of the seat section to engage and fasten the seat section to a seat board 13 of 85 the character described. As shown the clasp 14 is bail-shaped and formed by the intermediate portion of a length of spring wire, the ends of which extend rearwardly in the form of parallel attaching arms 15 90 having bent rear ends 16 seated in recesses 17 in the seat section and secured at their forward ends to the seat section by staples 18. The mode of using this clasp will be evident, and it will be seen that it provides 95 a means whereby the chair or seat may be readily and conveniently applied to and removed from a seat board. The U-shaped handle 19 is applied to and connects the lower ends of the side rails 5 of the back 100 section and serves as a handle by means of which the folded chair or seat may be transported, as shown in Fig. 4, and also as a foot rest or stirrup for the convenience of a person seated in rear of the occupant of the 105 particular chair. This combined handle and foot rest may be dispensed with when desired.

The construction of my improved folding chair or seat and its mode of use will be 110 readily understood from the foregoing description, and it will be seen that the inven-

tion provides a chair or seat of the character set forth which may be manufactured and sold at a low cost, readily stored and transported in convenient and compact shape, and 5 is adapted to be used upon seat boards in such a way as to enable the user to have a comfortable seat. Other advantages of the invention will be evident from the foregoing description.

10 I claim:-

1. A folding chair comprising a back section having side pieces provided with lower projecting ends, a seat section having a front cross piece provided with ends projecting 15 beyond the side edges of said seat section, the rear end of the latter being mounted between and pivotally connected with the projecting ends of the side pieces of the back section, links pivotally connected at 20 one end with the extended ends of the side pieces of the back section above the pivot points of the seat section and having their opposite ends slidably and pivotally connected with the extended ends of the cross

piece of the seat section, the said pivotal 25 connections between the back and seat sections including pivot members arranged to engage and brace the links when the seat section is outfolded, and means upon the seat section for securing the same to a seat 30 board.

2. A folding chair comprising a back section, a seat section, headed pins hingedly connecting said sections, links pivoted to the back section and having slotted ends slidably and pivotally connected with the seat section, said links adapted to be braced from said headed pins when the seat section is unfolded, and a clasp upon the underside of the seat section for securing the same to a 40 seat board.

In testimony whereof I affix my signature in presence of two witnesses.

ONAH MAUDE JACKSON.
